UNITED STATES PATENT OFFICE

2,325,195

TOGGLE FOR CRUSHERS

Edward T. Peterson, Reading, Pa.

Application August 16, 1941, Serial No. 407,195

1. Claim. (Cl. 83—53)

The invention relates to the art of toggles.

One purpose of the invention is to provide toggles with removable and replaceable ends.

A further purpose is to construct toggle bodies with bifurcated edges at the ends and to hold removable end bumpers or wear parts within the bifurcations by fins or tongues fitting therein and riveted to place, whereby the fins or tongues are supported by the side walls against tilting in either direction.

A further purpose is to provide toggles with removable buffer or wear strips along the ends in the form of beads held within forked end edges and having shoulders abutting the outer limits of the forks to support against tilting.

A further purpose is to hold a toggle buffer or bead by a fin between spaced, inwardly springing forked end strips and to provide end adjustment by shims between bead shoulders and outer faces of the end strips.

A further purpose is to provide bead buffers for the ends of toggles, having shoulder thrust lengthwise of the buffers, to secure rigid support against yielding lengthwise, and to adjust the lengths of the beaded toggles by shims between the shoulders and the end edges of the toggle body.

Figure 1 is a top plan view of a preferred form of toggle.

Figure 2 is a cross section of Figure 1 upon line 2—2.

Figure 3 is a cross sectional perspective of the beaded bumper or wear strip of Figure 2.

Figure 4 is a fragmentary enlarged section corresponding to a part of Figure 2.

Figure 5 is a perspective view of the end of an adjusting shim.

Figure 6 is a face elevation of a shim.

In the drawing similar numerals indicate like parts.

Previous toggles have either been integral, so that wear of either end edge has required replacement of the entire toggle or have been built up of parts which lacked rigidity and were not capable of adjustment. It is the purpose of the present invention to provide a toggle having removable end beads to take end wear and capable of lengthwise adjustment, the beads being securely attached and yet easily replaceable, and the entire structure being rigid in all adjusted positions.

The body 6 of the crusher toggle shown is reinforced by longitudinal ribs 7, 8, 9, 10 and by transverse ribs 11. Lifting rings 12 are cast, within one each of two ribs 7.

The end edges 13 of the body are grooved by

slots 14 which may be cored at their inner ends at 15 but whose inner walls are finished desirably along their oppositely facing inside surfaces at 16 and 17 and at 18 and 19 outside (considered with respect to the length of the toggle) of a row of rivet or bolt holes 20 transverse to the toggle.

It will be evident that each groove divides the outer part of the toggle body into spaced ribs, strips or fins which may extend the full width of the toggle and each of which is "finished" at its outwardly facing edge surface 21.

The grooves receive inwardly extending tongues 22 of beads 23, which beads comprise removable buffers taking the wear at the ends of the completed toggle. The beads carry inwardly facing shoulders 24 to engage the end surfaces 21, or to engage shims 25 used for adjustment purposes and located between the outwardly facing surfaces 23 and the inwardly facing shoulders 24.

Between the shoulders 24 the tongues 22 extend inwardly from the buffers and are of such thickness as to be drive fits between the finished inner walls 16, 17, 18 and 19 of the strips or fins. The grooves are made deep, considerably beyond the inner tongue edges so as to provide ample follow-up of the resilient strip pressure against the tongues. The side pressure of the strips is effective both to reduce the tendency of the tongues to move within the grooves—and hence to wear—and to maintain adequate side pressure notwithstanding wear.

The tongues are provided with rivet holes 26 in line with the rivet or bolt holes 20 and elongated lengthwise of the toggles to accommodate adjustment of the beads.

Preferably the toggle bodies and the buffers are held in place by rivets 27 passing through the rivet holes in the tongue.

In assemblage any shim or shims required are put in position about the tongues attached to the buffers and the tongues are inserted to a position where a shim or the shims is or are gripped between the shoulders 23 and 24 and surfaces 21, or, in the absence of shims, the shoulders directly engage tightly against the outwardly facing surfaces 21 at the shortest limit of length adjustment.

The tongues do not extend the entire width of the toggle but are not present at the ends at 28 and 29, in order to accommodate the transverse end portions 30 and 31 of shims 25, seen in Figures 5 and 6.

The deep grooving of the edges gives a correspondingly highly resilient spring side grip 16

and 17, of the edges 18 and 19 against each tongue between them, holding the tongues initially and helping to hold them additionally to the clamping hold effected by the setting of the bolts or rivets.

It will be evident that the toggle provides an unaltered unitary body extending almost the entire length of the toggle along with removable wear beads, spring held between resilient forked edges with rivet fastenings tightening the edge strips upon a bead tongue between them and with a range of adjustment longitudinally which cooperates with the type of construction used. The construction is rugged and rigid and the beads are quickly and easily replaceable.

The present application is a continuation in part of my application for Toggle, Ser. No. 267,440 filed April 12, 1939.

In view of my invention and disclosure, variations and modifications to meet individual whim or particular need will doubtless become evident

to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

A unitary crusher toggle body having grooved 10 end edges providing spaced resilient edge strips and outwardly facing end edge surfaces, beads for the edges having inwardly directed tongues, each resiliently held between two strips and inwardly facing shoulders adjacent the edge strip 15 surface and adapted to engage them, a shim surrounding a tongue and fitting between the shoulders and the adjoining surfaces, and fastenings extending through the strips and tongues and holding the beads to the body.

EDWARD T. PETERSON.
